PAPER FASTENER

Daniel A. Brennan, Chicago, Ill.

Application September 5, 1933, Serial No. 688,099

34 Claims. (Cl. 24—153)

This application is a continuation-in-part of my co-pending application, Serial No. 476,058, filed August 18, 1930.

The invention relates to improvements in fasteners for binding a stack of papers, such as letters in files, and particularly to an improved paper fastener including a base having prongs adapted to extend through apertures in the stack of papers, and a compressor having similarly spaced apertures adapted to receive said prongs therethrough, the free end portions of the latter being adapted to be bent downwardly over said compressor and to be held in place by latches.

One object of the invention is to provide an improved fastener of the foregoing type with novel means for effecting a yieldable engagement between the prongs and the latches, to resist displacement after the latter are moved into position to hold the prongs over the compressor.

Another object is to provide an improved fastener of the type described with novel means for effecting a frictional engagement between the prongs and the latches to resist displacement of the latches after they are moved over and into engagement with the prongs, in any of their variable positions on the compressor.

Another object is to provide an improved fastener of the type described with latches having means movable into yieldable frictional engagement with means on the compressor and on the prongs to hold said latches in predetermined variable positions on the compressor.

Another object of the invention is to provide an improved fastener, inexpensive to manufacture and simple in operation.

The foregoing and such other objects of the invention as will more fully appear hereinafter will be more readily understood from a perusal of the following specification, reference being had to the accompanying drawing, in which:

Fig. 1 is a perspective view of a fastener embodying features of the invention.

Figs. 2 and 3 are plan views of two modified forms of fasteners.

Fig. 4 is a transverse sectional view taken on line 4—4 of Fig. 3.

Paper fasteners of the type comprising a base with prongs adapted to pass through apertures in a stack of papers, and a compressor having registering apertures adapted to receive said prongs, in some instances are provided with latches slideable over the prongs after the latter are bent downwardly over the compressor. In such devices, the latches often are arranged to slide inwardly over the prongs from a position outwardly

of the apertures, and in other instances are slideable outwardly over the prongs from a position intermediate the apertures.

The invention relates, primarily, to the novel construction of a fastener in which the latches are adapted to be detachably secured in adjusted position over the bent-down prongs.

Referring particularly to Fig. 1 the fastener, constituting one embodiment of the invention, comprises a base 11 having prongs 12 on opposite ends, and an elongated compressor 13 having spaced apertures or perforations 14 adapted to receive the prongs. The prongs preferably are substantially less in width than the body of the base and are struck up substantially at right angles thereto.

Spaced parallel elevated guides or tracks 15 are provided along the opposite longitudinal sides of the compressor 13. Preferably, the guides 15 are formed by folding the marginal side edges of the compressor 13 upwardly and then inwardly as shown, and extend between the apertures 14. The guides 15 serve to reinforce the compressor 13, and to confine the prongs 12 laterally when the latter are bent downwardly over and against the compressor. Preferably, the ends of the guides 15 are struck downwardly against the base of the compressor 13 inwardly of or adjacent the apertures 14 to constitute stops 16.

In the form of fastener shown in Fig. 1 the projecting end portions of the prongs 12 are bent inwardly from the apertures 14 towards each other. Two latches 17, each formed of a strip of metal extending transversely of the compressor 13, are mounted to slide along the guides 15 between the stops 16. Each latch preferably is provided with an intermediate elevated or bridge-like portion 18, and two shoe portions 19 connected thereto by substantially vertical walls 21 underlie the guides 15. The latches 17 are initially located inwardly of the downwardly bent prongs 12, and are then movable outwardly over the ends of the prongs to hold the latter against the compressor 13. To secure the latches 17 releasably in position over the underlying ends of the prongs 12, each of said ends is formed, preferably in each edge, with a notch or recess 22, and each latch is formed with a lateral detent 23 stuck inwardly from one of the side walls 21 and adapted to engage in the associated recess. Preferably, the recesses 22 and the co-acting detent or side walls are arcuate in contour. The latches 17 preferably are made of yieldable material so that the side walls 21 can flex or spread upon receiving the ends of the prongs 12 to cause the detents 23

23 to frictionally engage in the recesses 22. It will be evident that the interlocking frictional engagement between the prongs 12 and the side walls 21 co-acts to secure the latches 17 yieldably in the most advantageous latching position.

The fastener shown in Fig. 2, is like that shown in Fig. 1, except that here the latches 17 have a detent 23 on each side wall, each of which is embracingly engaged by a notch 22 in the prong. 10 In this form the stops 16 on guides 15 are located inwardly of the apertures 14.

The fastener illustrated in Figs. 3 and 4, is generally similar to the fasteners just described, and like parts are therefore identified by the same 15 reference characters. In this instance, the elevated portions of the guides 15 extend outwardly beyond the apertures 14 so that the latches 17a are adapted to be moved inwardly over the downwardly bent prongs 12. The guides 15 preferably 20 are depressed centrally of their ends, as indicated at 26, or may be provided with downwardly extending projections, to prevent the latches 17 from sliding inwardly past the intermediate portion of the compressor 13.

25 The latches 17a have ends 19 slidably underlying the guides 15 as in the forms of Figs. 1 and 2, but differ from said forms in that they have intermediate elevated or bridge-like portions 25 which extend outwardly beyond the inner longitudinal margins of the guides to define overlying flanges 24, and then are struck under to join with curved side walls 21a. Preferably the intermediate portions 25 are slightly curved downwardly over the prongs 12. Also, both side edges 30 of the prong 12 are formed with recesses 22, and both side walls 21a of the latches 17a preferably are formed with inwardly projecting detents 23 or the equivalent for engaging in the recesses to frictionally hold the latches releasably in binding 35 position over the prongs.

To retain the latches 17a yieldably outwardly of the apertures 14, the base of the compressor 13 may be formed at each end, beneath one guide 15, with an upstanding projection 27 40 adapted to engage with a recess 28 in the underside of one shoe portion 19 of the associated latch upon movement of the latter into its outermost position, or an upstanding projection 27a may be provided on the compressor inwardly of the 45 guides to co-operate with one side wall 21a of the latch and frictionally retain it outwardly of the aperture.

Although various exemplary forms and adaptations of the improved fastener have been illustrated in the accompanying drawing and described in detail in the foregoing specification, it is to be understood that the features of the present invention may be incorporated in other fasteners of the general type shown, or otherwise 50 varied in structural detail and arrangement without departing from the spirit and scope of the invention as expressed in the appended claims.

I claim:

65 1. A paper fastener having, in combination, a base with spaced prongs, a compressor having spaced apertures adapted to receive said prongs, said prongs being adapted to be bent downwardly against said compressor, and latches secured to 70 said compressor for longitudinal sliding movement respectively over said prongs, said latches having side walls movable into frictional engagement with said prongs to hold said latches releasably in position of adjustment over said prongs.

75 2. A paper fastener having, in combination, a

base with spaced prongs, a compressor having spaced apertures adapted to receive said prongs, said prongs being adapted to be bent downwardly against said compressor, and latches secured to 5 said compressor for longitudinal sliding movement respectively over said prongs, one side edge of one prong being formed with a recess, the latch associated with said one prong having a detent movable yieldably into engagement with said recess to hold said latch frictionally in position.

3. A paper fastener having, in combination, a base with spaced prongs, a compressor having spaced apertures adapted to receive said prongs, 10 said prongs being adapted to be bent downwardly against said compressor, and latches secured to said compressor for longitudinal sliding movement respectively over said prongs, each prong being formed in one side edge with a recess, each latch having a detent movable yieldably into engagement with the recess of the associated prong to hold said latch frictionally thereover.

4. A paper fastener having, in combination, a base with spaced prongs, a compressor having spaced apertures adapted to receive said prongs, 25 said prongs being adapted to be bent downwardly against said compressor, and latches secured to said compressor for longitudinal sliding movement respectively over said prongs, each prong being formed in opposite side edges respectively with two recesses, each latch being formed in opposite sides with two detents movable into engagement with the recesses of the associated prong, whereby said latches are adapted to be held frictionally in position over said prongs. 30

5. A paper fastener having, in combination, a base with two spaced prongs, a compressor having two spaced apertures adapted to receive said prongs, said prongs being adapted to be bent downwardly against said compressor, two latches 40 slideable along said compressor for movement respectively over said prongs, each prong having an offset recess and each latch being movable into engagement with the recess of the associated prong, said recesses partially embracing said 45 latches, and co-action therebetween acting to secure said latches releasably in predetermined positions respectively over the free ends of said prongs.

6. A paper fastener comprising a base having 50 prongs, a compressor provided with spaced openings to receive said prongs, said prongs being bent over against said compressor, said compressor having its longitudinal edges folded over to form 55 guides, latches having their ends formed to embrace said guides, and an intermediate bridge-like portion formed in each latch between said longitudinal guides, said latches being movable respectively over said prongs to hold the latter down against said compressor, said latches each being formed to detachably engage at least one edge of the underlying prong adjacent its end to frictionally hold the latches in position over said prongs.

7. A fastener comprising, in combination, a compressor having spaced openings one in each end, a base having similarly spaced prongs, said prongs being adapted to be inserted through said openings and then bent inwardly towards each other against said compressor, the sides of said 70 compressor having longitudinal guides, and latches being slideable on said guides one over each of said prongs to hold the latter down against said compressor, each of the latches resiliently 75

engaging offset recesses in the underlying prong to retain it over said prong.

8. A paper fastener having in combination, a base having bendable prongs, a compressor with spaced openings to receive said prongs, the prongs being adapted to be bent down against the compressor, longitudinal guides on said compressor, and latches slideable along said guides one over each bent down prong, and means in said latches adapted to move into binding engagement with at least one edge of the underlying prong.

9. A paper fastener comprising a base having bendable prongs, a compressor having spaced openings to receive said prongs, the end portions of said prongs having recesses and being bent inwardly towards each other against said compressor, said compressor having its longitudinal edges forming guides, and latches having upper and lower marginal end flanges embracing said guides and intermediate bridge-like portions formed by said latches extending between said longitudinal guides, said latches being movable from an intermediate position between the bent down ends of said prongs outwardly respectively over said prongs to hold the latter down against the compressor, said latches having means to detachably engage the recesses on the underlying prong to yieldingly hold said latches in position over the ends of said prongs.

10. A fastener comprising, in combination, a compressor having spaced openings one at each end, a base having similarly spaced prongs, said prongs being adapted to be inserted through said openings and then bent inwardly toward each other against said compressor, and two latches movable along said compressor from a position intermediate the ends of the bent down prongs outwardly respectively over said prongs toward said openings, each of said latches being formed to embracingly engage said prongs whereby said latches are held over the prongs.

11. A paper fastener comprising a base having spaced resilient bendable prongs, a compressor over which said prongs are adapted to be bent, and a latching member movable on the compressor longitudinally thereof and having a bridge portion extending transversely over said compressor, at least one of said prongs being formed to provide embracing and resilient interlocking engagement between the prong and said latching member when the latter is located in a predetermined position with respect to said prong.

12. A fastener comprising, in combination, a flat elongated base provided with two longitudinally spaced prongs adapted to be bent upwardly into substantially parallelism, said prongs having recesses on their free ends, a flat elongated compressor having two longitudinally spaced apertures for said prongs to pass through, said prongs being adapted to be bent downwardly against the top of said compressor, and two latches slideably mounted on said compressor for movement respectively over the downwardly bent portions of said prongs to retain the latter against said compressor, each of said latches being movable into interlocking engagement with the recesses in the underlying prong.

13. A fastener comprising, in combination, a flat elongated base provided with two longitudinally spaced prongs adapted to be bent upwardly into substantially parallelism, said prongs having recesses on their free ends, a flat elongated compressor having two longitudinally spaced apertures for said prongs to pass through, said prongs being adapted to be bent downwardly

against the top of said compressor, and two latches slideably mounted on said compressor for movement respectively over the downwardly bent portions of said prongs to retain the latter against said compressor, each of said latches being movable into said recesses in the underlying prong. 5

14. A paper fastener having, in combination, a base having spaced prongs, a compressor having spaced openings to receive said prongs, said prongs being adapted to be bent downwardly 10 against said compressor, the longitudinal edges of said compressor being folded over to form guides, bridge-like latches slideable along said guides, the central portions of said latches being elevated to pass over said prongs, said latches being movable 15 from an intermediate position outwardly respectively over said prongs toward said openings, said guides being depressed at their ends to limit outward movement of said latches, and complementary co-acting means formed on the side edges of 20 said prongs adjacent their free ends and on said latches to provide interlocking elements to yieldingly hold said latches over the ends of said prongs.

15. A paper fastener comprising a base having 25 prongs, a compressor having spaced openings to receive said prongs, said prongs being adapted to be bent inwardly towards each other against said compressor, longitudinal guides on the compressor, bridge-like latches having their ends arranged to slide along said guides and their central portions elevated to pass over said prongs, said latches being movable from an intermediate position outwardly respectively over said prongs toward said openings, means on said guides to 30 limit outward movement of said latches, and means on one edge of at least one prong and on at least one latch formed to provide interlocking elements to yieldingly hold said latch over the end of said prongs. 35

16. A paper fastener comprising, a base having prongs, a compressor having spaced openings to receive said prongs, said prongs being bent inwardly towards each other against said compressor, the longitudinal edges of said compressor being folded over to form guides, said guides extending outwardly beyond said openings, latches slideable along said guides, a central elevated portion on each latch adapted to pass over said prongs, means on said guides to limit outward movement of said latches and frictionally retain them outwardly of said openings, said latches being movable from beyond said openings inwardly respectively over said bent down prongs, and means on the edges of said prongs adjacent 55 their ends and on said latches formed to provide interlocking elements to yieldingly hold said latches over the ends of said prongs.

17. A paper fastener comprising, a base having prongs, a compressor having spaced openings 60 to receive said prongs, the prongs being adapted to be bent inwardly toward each other against said compressor, longitudinal guides on said compressor, said guides extending outwardly beyond said openings, latches having their ends engaging 65 in said guides and their central portions elevated to pass over said prongs, means on said guides to limit outward movement of said latches and frictionally retain them outwardly of said openings, said latches being movable from beyond 70 said openings inwardly respectively over the bent down prongs, and co-operating means on one edge of each of the prongs adjacent its end and on the associated latches formed to yieldingly hold said latches in position. 75

18. A fastener comprising, in combination, a compressor having spaced openings one in each end, a base having similarly spaced prongs one on each end, said prongs being adapted to be inserted through said openings and then bent inwardly towards each other against the compressor, the sides of said compressor being formed to provide longitudinal guides, said guides extending outwardly beyond said openings, latches 5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250
